UNITED STATES PATENT OFFICE.

VICTOR V. LAWRENCE, OF WATERFORD, VERMONT, ASSIGNOR OF ONE-HALF
TO ISAAC F. PAUL, OF BOSTON, MASSACHUSETTS, AND AMOS H. CARPENTER, OF WATERFORD, VERMONT.

CUTTER-HEAD FOR PLANING-MACHINES.

SPECIFICATION forming part of Letters Patent No. 399,758, dated March 19, 1889.

Application filed March 26, 1888. Serial No. 268,488. (No model.)

To all whom it may concern:

Be it known that I, VICTOR V. LAWRENCE, of Waterford, in the county of Caledonia, State of Vermont, have invented a certain new and useful Improvement in Cutter-Heads for Planing-Machines, of which the following is a description sufficiently full, clear, and exact to enable any person skilled in the art or science to which said invention appertains to make and use the same, reference being had to the accompanying drawings, forming part of this specification.

I also show in the said drawings and hereinafter describe an improved presser-bar, of which I am the inventor, but which is not herein claimed, since it forms the subject of an application for patent filed August 20, 1888, Serial No. 284,104.

In the drawings, two sheets, Figure 1 is an end elevation of an ordinary cutter head or cylinder provided with two knives or cutters; Fig. 2, a side elevation of the same, a portion of the head and knives being represented as broken off; Fig. 3, a rear elevation of my improved cutter-head and presser-bar, a portion of the same being represented as broken off; Fig. 4, an end elevation; Fig. 5, a vertical transverse section taken on line *xx* in Fig. 3; Fig. 6, a top plan view showing an alternate form of constructing the cutter-head and presser-bar; Fig. 7, a side elevation of the same with the presser-bar removed; Fig. 8, a vertical transverse section taken on line *yy* in Fig. 7; and Fig. 9 is a detail view.

Like letters and figures of reference indicate corresponding parts in all the figures of the drawings.

The rotary cutter-heads of planing-machines have been constructed with a central lengthwise slot or opening, and transversely curved cutters have been secured within the same, and so arranged as to project the required distance on opposite sides of the head; but the most common construction and arrangement is that shown in Figs. 1 and 2, in which A represents a solid rectangular head, 4 the knives or cutters, and 57 the bolts by which the knives are secured.

The cutter-head is square, or nearly so, the knives being placed on opposite sides thereof,

and with their cutting-edges projecting in opposite directions, as shown at 14 in Fig. 1.

The attaching-bolts 57 for the knives are usually placed opposite the journal 46 of the head, and as the distance between the protruding edges 14 of the knives and said bolts is considerable, and the cutter-head solid or not provided with lateral openings for the escape of the chips, the chips are liable to be caught and "wedged" between the bodies of the knives and their beds, thereby throwing the knives "out of truth," and sometimes springing or bending them laterally to such an extent as to render it necessary to remove them for repairs.

The head being solid or unprovided with lateral openings also causes the chips to be forced against its sides at the point 16, immediately below the cutting-edges of the knives, thereby retarding the revolutions of the head and producing a loss of power in running the machine.

My invention is designed to obviate these and other objections to the ordinary cutter-head, and to that end I make use of means which will be readily understood by all conversant with such matters from the following explanation.

In the drawings, (see Figs. 3 to 5, inclusive,) A represents the cutter-head or cylinder, B the standards in which the head is journaled, and C the presser-bar.

The body of the cutter-head consists, essentially, of two vertically-arranged end pieces, 45, each provided with an outwardly-projecting centrally-arranged horizontal gudgeon, 46, which is journaled in a box or bearing, 16, in the standard B. The end pieces, 45, are rigidly connected by two wide horizontally-arranged bars, 3, which are disposed opposite each other, and preferably cast or formed integral with the end pieces and gudgeons. The bars 3 are rounded or curved in cross-section on their peripheries, and have the inner faces of their forward portions inclined tangentially, or nearly so, to the axis—that is to say, at an angle of about forty-five degrees to a line drawn through the centers of both bars—and crossing the longitudinal axial line of the cutter-head at right angles thereto, said

inclined portions of the bars serving as beds 47 for the knives 4, which are adjustably secured thereto by screws 57, said screws passing through slots in the knives into said beds.

5 Stop-screws 12 are also provided on the inner sides of the bar 3, against the ends of which the backs of the knives abut, the stop-screws also subserving to assist in adjusting the knives.

10 The presser-bar C is crescent-shaped in vertical cross-section, being of such length as to extend beyond the knives 4, and is attached at each of its ends to a horizontal arm, 90, which is pivoted by a strap-connection, 17, on 15 the box 16 of gudgeon 46. The free outer end of the arm is slotted lengthwise, and the presser-bar is adjustably attached by a clamp-screw, 18. (See Fig. 4.)

The lower side of the head 8 of the presser-bar C is beveled or inclined to form a bed or seat, 19, on which a rigid plate, 20, rests. This plate is preferably coequal in length with the presser-bar head and is beveled on its lower side to form a cutting-edge, 21, the 25 beveled portions bearing on the top of the board D in close proximity to the point or line where the cutting-edges of the knives 4 leave the surface of said board in removing the chip or shaving therefrom during the 30 process of planing. Said plate is adjustably secured to the bed 19 of the presser-bar head by screws 58, which pass through slots, (not shown,) and is also provided with stop-screws 9, which are fitted to work in brackets 99 on 35 said head, said stop-screws resting against the back of the plate, and also subserving to assist in adjusting it.

The cutting-edge 21 of the plate 20 on the presser-bar acts conjointly with the cutting-edges of the knives 4 of the cutter-head to sever the chips or shavings as they are raised from the board by the knives, thus preventing the knives to a large extent from stripping or tearing the chips or shavings from 45 the board and leaving its planed surface more or less striated or grooved in the usual manner. The body of the cutter-head A being hollow or provided with a large lateral opening which extends exteriorly across it between the bars 3 and end pieces, 45, as shown 50 in Fig. 5, the chips will pass into said opening as the head revolves, and thus afford but comparatively little resistance to its revolutions, while the knives, being mounted within 55 the cutter-head with their edges projecting outward, receive the chips or shavings on their upper sides, thereby rendering it impossible for the chips to become wedged between said knives and their beds 47, as is the case in the 60 use of the ordinary cutter-head shown in Figs. 1 and 2.

I sometimes construct the cutter-head with more than two knives, and mount the plate 20 on the inner instead of the outer side of 65 the presser-bar, as shown in Fig. 8. I also sometimes mount the stop-screws 12 for the knives 4 in brackets 5, secured to the end

pieces, 45, of the head A, and provide said screws with annular flanges 95, (see Fig. 9,) which are inserted in T-shaped slots 13 in 70 the backs of the knives, the stop-screws 9 for the plate 20 of the presser-bar being mounted in brackets 99, secured to the head 8 and connected with said plate in like manner. I also sometimes curve the plate 20 downward 75

to enable it to pass under the cutter-head more readily, and bevel it on its upper instead of its lower side at its cutting-edge, as shown in Fig. 8. I also sometimes construct the bars 3, Fig. 8, slightly higher at their extreme rear 80 edges than at their front edges to form burnishers 48—that is to say, such parts 48 have a greater radius than the front portions or edges of the bars 3, where the knives 4 project, and hence when the cutter-head is adjusted as close as practicable to the board or timber to be planed the parts 48 will work in contact with the planed portions of the board as the head revolves and thereby polish it. The burnishers are not, however, required for 90 this purpose for all kinds of work. In addition to the function above specified, the burnishers assist more or less in keeping the board properly on the bed of the machine. 85

The head 8 of the presser-bar may also be 95 rendered adjustable on the arms 90, as shown at 92 in Fig. 8, if preferred, the ends of said arms being placed on the inner instead of the outer sides of the ends of the head.

In Fig. 8 the presser-bar C is represented 100 as removed from the cutter-head A to its remotest point; but it will be understood that it is to be adjusted to bring its plate 20 into proper relation to the cutting-edges of the knives 4 when in use. 105

When the plate 20 is mounted on the inner side of the presser-bar head, as shown in Fig. 8, holes 6 are provided in said head for receiving the screw-driver used in turning the screws 9. 110

A pulley, N, is provided for driving the cutter-head in the usual manner.

As my improvement relates exclusively to the cutter-head, it is not deemed essential to show many of the other parts of the machine. 115

For convenience of reference, I denominate the side of the bar 3 to which the knife 4 is secured its "front" side.

Having thus explained my invention, what I claim is— 120

1. The improved rotary cutter-head having heads or end pieces, 45, provided with short integral journals or gudgeons 46, projecting from their outer sides, and the parallel portions 3, which connect said end pieces, the same being separated by a clear space extending their whole length, and having flat inclined knife-beds 47, which are tangential to the axis of the cutter-head, as shown and described. 125

2. The cutter-head A, having the knife-carrying bar 3, said bar being constructed higher at its rear than at its front side to form the burnisher 48, substantially as described. 130

3. The end pieces, 45, provided with the

gudgeons 46 and connected by the bars 3, the knives 4, secured to the front inner sides of said bars by the screws 58, the brackets 5, attached to said end pieces, and the adjusting-screws 12, mounted in said brackets and connected with said knives by the annular flanges 95, and slots 13, all being constructed, com-

bined, and arranged to operate substantially as described.

VICTOR V. LAWRENCE.
